FRANK C. GIBBS, OF DAVENPORT, IOWA.

BOILER-COMPOUND-FEEDING APPARATUS.

1,120,047.

Specification of Letters Patent.

Patented Dec. 8, 1914.

Application filed October 18, 1914. Serial No. 867,034.

To all whom it may concern:

Be it known that I, FRANK C. GIBBS, a citizen of the United States of America, residing at Davenport, in the county of Scott and State of Iowa, (whose post-office address is Davenport, Iowa,) have invented a new and useful Boiler-Compound-Feeding Apparatus, of which the following is a specification.

10 My invention relates to devices for feeding boiler-compound in solution into steam boilers, and the objects of my invention are: First, to provide means for mixing a predetermined quantity of boiler-compound with the feed water just before being fed into the boiler; second, to provide a sight glass or transparent section in the feeding tube by which the amount and color of the compound solution can be observed; third, to provide 15 means for alternately drawing the boiler-compound in solution into a transparent sight glass where it can be observed and for washing out the sight glass after expelling the compound therefrom so as to keep the sight glass clean and facilitate observation 20 of its contents; fourth, to provide convenient means for readily regulating the quantity of compound to be fed at each stroke; fifth, to provide means to prevent the escape 25 of the boiler-compound solution when the pump is idle; sixth, to provide means for mixing the boiler-compound thoroughly with water and for keeping same thoroughly 30 mixed. I attain these objects by means of 35 the apparatus illustrated in the accompanying drawings in which—

Figure I is a side elevation of my preferred form of apparatus. Fig. II is a cross section detail of the check valve C and Fig. 40 III is a side view of the check valve b but with part of the casing broken away to show the interior construction.

Similar characters refer to similar parts throughout the several views.

45 A feed pump h, constructed in the ordinary manner is provided with an intake pipe i, and discharges into the steam boiler in the usual well known manner. The intake pipe i, is preferably connected to a water heater.

50 It is obvious that the feed water may be obtained from a heater tank or any other container without varying from the spirit of my invention.

A supply tank e, is secured in position a 55 suitable distance above the feed pump h. The supply tank is provided with an in-

take pipe p, and a funnel for the insertion of the boiler-compound either in dry, liquid or other form as may be desired, and the intake pipe, p, is provided with a valve of the ordinary hand wheel type to close same.

An intake pipe, f, connecting with the feed water heater may be secured to the tank, e, to equalize the pressure on the supply tank, e, and the intake, i. An ordinary hand valve closes same when necessary. A steam pipe, g, is led into one end of the supply tank near the bottom thereof and under the filler pipe and is provided with a valve o, by which same may be closed or the admission of steam regulated. A glass gage, q, is suitably secured to the supply tank in a vertical position, both ends opening into the supply tank so that the level of the solution and its strength may be observed in the glass tube.

A pipe line, j, extends from the supply tank, e, to one end of the pump, h, and has suitably connected therewith a section of glass tubing or sight glass, a, suitably secured in and as a part of the pipe line. The adjoining sections of the pipe line are held in position by a yoke, n. This sight glass, a, may be mounted in any desired manner but my preferred form is to mount same with a stuffing box at each end and secured by sleeves threaded to fit into the metallic portion of the pipe line and provided with nuts, m, by which same can be tightened or loosened.

90 A check valve, b, is secured in the pipe line between the tank, e, and the sight tube or gage, a, to prevent the fluid from flowing backward into the stock tank, e. A hand valve, l, is mounted in the lower end of the pipe line, j, where same connects with the pump.

95 A regulating valve, d, is mounted in the pipe line between the stock tank, e, and the junction of its branches. Any suitable form of valve may be used but I have shown the ordinary plug cock which may be opened or closed by turning the handle. This valve regulates the flow of the fluid from the stock tank into the sight tube or gage, a, and may be adjusted so that a single stroke of the pump will draw just enough boiler-compound out of the stock tank to fill the sight tube half full or full, or any other quantity as desired.

100 At the upper end of the pipe line, j, a check valve, c, is mounted connecting with

the pipe line, *k*, which extends from the check valve, *c*, to the intake pipe, *i*, of the pump *h*. The upper end of the pipe line, *k*, is constructed higher than the top of the supply tank, *e*, so that the stock solution will not run out by gravity upon stoppage of the pump but the escape of the stock solution may also be prevented by closing the regulating valve *d*.

10 I have shown the check valve, *d*, of the ordinary swing check type, consisting of a seat, *u*, and a valve, *t*, pivoted at its upper end, and I have shown the check valve, *c*, as the ordinary gravity check consisting of a seat, *s*, and valve, *r*, secured in place by a central stem extending on each side of the valve and working in suitable openings formed in the casing. It is obvious that any other suitable form of check desired 15 may be used with this apparatus and I make no special claim upon any particular form of valve.

10 In the operation of my apparatus, the supply tank, *e*, is filled with water to the desired height. The boiler-compound is then introduced through the funnel and intake pipe *p*, either in solution or in original form, and is thoroughly mixed with the water in the stock tank, *e*, by steam admitted through the valve *o*. The valve, *d*, is then opened to the desired extent and permits the boiler-compound solution to go into the pipe line, *j*, with each alternate impulse of the pump *h*. When the piston 25 is drawn away from the end of the cylinder to which the valve *l*, connects, the suction draws water from the pipe line, *j*, into the cylinder of the pump and causes the solution to flow from the stock tank into the pipe line. The cylinder at the same time 30 is receiving water from the intake pipe *i*. The proportion of water received from the intake pipe, *i*, and from the pipe line, *j*, is determined by their relative sizes and 35 the extent to which the valve, *d*, is opened. I prefer to have the valve *d*, opened sufficiently to permit enough solution to be drawn from the tank to fill the upper half 40 of the sight tube or gage, *a*, at each impulse. The solution can then be observed in the sight tube without coloring the whole tube. At the return stroke of the pump, a part 45 of the water in the cylinder of the pump is forced into the pipe line, *j*, through the valve, *e*, closing the check valve *b*, and forcing the solution from the sight tube, *a*, with an added quantity of water through the valve *c*, and through the feed line *k*, into the intake pipe *i*, where it is mixed with 50 the feed water before going into the boiler. The pressure upon the solution in the stock tank *e*, and pipe line, *j*, and the water in intake, *i*, is very small relatively to the pressure of the pump upon the return stroke of 55 the piston which forces the water into the

boiler as well as forces water into the pipe line *j*, so that a much larger quantity of water is forced into the pipe line, *j*, than is drawn from the stock tank solution, thus thoroughly washing out the sight tube *a*, 70 as well as reducing the strength of the solution before it enters intake *i*.

It is obvious that the feed line *K*, may be connected to the intake *i*, at any convenient point or may feed directly into the boiler without departing from the spirit of my invention, but I prefer to have it connected with the intake pipe so as to more thoroughly mix the boiler-compound solution with the water. 80

It will be observed that my apparatus provides a positive feed without mechanical moving parts other than the check valves and feed-water pump.

What I claim is:

1. In combination with a boiler feed-water pump, a suitable tank, a pipe line extending from the tank and having two branches one of which connects with the pump cylinder and the other with the pump intake, a check valve in the pipe line before it branches, and a check valve in the branch connecting with the intake between the intake and the junction of the two branches. 90

2. The combination with a boiler feed-water pump, of a suitable tank, a pipe line, extending from the tank and having two branches one of which connects with the pump cylinder and the other with the pump intake, a check valve in the pipe line between the tank and the junction point of the two branches, a check valve in the branch connecting with the intake between the intake and the junction point of the two branches, and a regulating valve mounted in the pipe line between the tank and the junction point of the two branches. 100

3. The combination with a boiler feed-water pump, of a suitable tank, a pipe line extending from the tank and having two branches one of which connects with the pump cylinder and the other with the pump intake, a check valve in the pipe line between the tank and the junction of the two branches, a check valve in the branch connecting with the intake between the intake and the junction point of the two branches, a sight glass inserted in and forming a section of the branch extending to the pump. 110

4. The combination with a boiler feed-water pump, of a suitable tank, a pipe line extending from the tank and having two branches one of which connects with the pump cylinder and the other with the pump intake, a check valve in the pipe line between the tank and the point of departure of the two branches, a check valve in the branch connecting with the intake between the intake and the junction point of the two branches, a sight glass mounted in and 120

forming a section of the branch line extending to the pump, and a suitable yoke to secure the portions of the pipe line adjacent to the sight tube in position.

5. In a boiler-compound feeding apparatus, the combination with a suitable supply tank, of a pipe line connecting the tank with a pump and containing a sight glass, and means for alternately drawing a portion 10 of the solution from the tank into the sight glass and washing it out.

6. In a boiler-compound feeding apparatus, the combination with a feed-water pump, of a supply tank suitably secured 15 above the level of the pump, a branched pipe line connecting with the lower part of the tank and having one branch extending to the pump and the other branch having a double bend extending above the level of the 20 tank and a section extending from the bend to the pump intake.

7. In a boiler-compound feeding apparatus, the combination with a feed-water pump, of a supply tank suitably secured 25 above the level of the pump, a branched pipe line connecting with the lower part of the tank and having one branch extending to the pump and the other branch having a double bend extending above the level of the 30 tank and extending from the bend to the pump intake, and a regulating valve mounted in the pipe line between the tank and the junction of the branches.

8. In a boiler-compound feeding apparatus, the combination with a feed water pump, of a supply tank suitably secured 35 above the level of the pump, a branched pipe line connecting with the lower part of the tank and having one branch extending to the pump and the other branch having a double bend extending above the level of the 40 tank and extending from the bend to the pump intake, and a check valve mounted in the pipe line between the tank and the junction of the branches.

9. In a boiler-compound feeding apparatus, the combination with a feed water pump, of a supply tank suitably secured 45 above the level of the pump, a branched

pipe line connecting with the lower part of 50 the tank and having one branch extending to the pump and the other branch having a double bend extending above the level of the tank, a section extending from the bend to the pump intake, a check valve mounted in 55 the pipe line between the tank and the junction of the branches, and a check valve in the branch having the double bend between its entrance into the pump intake and the junction of the branches.

10. In a boiler-compound feeding apparatus, the combination with a feed water pump, of a supply tank suitably secured above the level of the pump, a branched pipe line connecting with the lower part of the 65 tank and having one branch extending to the pump and the other branch having a double bend extending above the level of the tank, a section extending from the bend to the pump intake, a check valve mounted in the 70 pipe line between the tank and the junction of the branches, a check valve in the branch between the double bend and the junction of the branches, and a regulating valve suitably secured in the pipe line between the 75 tank and the junction of the branches.

11. In combination with a boiler feed-water pump, a suitable tank having a glass gage suitably secured thereto, a pipe line extending from the tank and having two 80 branches one of which connects with the pump cylinder and the other with the pump intake, a check valve in the pipe line before it branches, and a check valve in the branch connecting with the intake between the intake and the junction of the two branches.

12. In a boiler-compound feeding apparatus, the combination with a suitable supply tank having a glass gage suitably secured thereto, of a pipe line connecting the 90 tank with a pump and containing a sight glass, and means for alternately drawing a portion of the solution from the tank into the sight glass and washing it out.
